CLAIM

The ornamental design for a ridge design for a bottle, as shown and described.

DESCRIPTION

FIG. 1 is a top perspective view of a ridge design for a bottle in accordance with the present invention;

FIG. 2 is a left side elevation thereof;

FIG. 3 is a front elevation thereof;

FIG. 4 is a right side elevation thereof;

FIG. 5 is a rear elevation thereof;

FIG. 6 is a top view thereof; and,

FIG. 7 is a bottom view thereof.

The dotted line showing of a bottle is for environmental purposes only and forms no part of the claimed design.
